UNITED STATES PATENT OFFICE.

WILLIAM T. BAILEY, OF NORWALK, OHIO, ASSIGNOR TO THE ROTARY PRINTING COMPANY, OF NORWALK, OHIO, A CORPORATION OF OHIO.

MANIFOLDING APPARATUS.

Application filed December 7, 1927. Serial No. 238,276.

This invention relates to a device for supporting a block of impression receiving sheets, together with means for securing copies in duplicate, triplicate, etc.

5 An object is to provide a simple convenient arrangement for holding the block of sheets in impression-taking position, and to removably secure one or more sheets of impression-transferring material, such as 10 carbon paper, in position to be inserted between adjacent sheets of the block.

A specific object is to adapt the parts, which serve to secure the transferring material, to formation from sheet metal, and 15 to form the parts in such manner that substantially all the marginal edges of the sheet metal are guarded.

Further objects and features of the invention will become apparent from the following 20 description relating to the accompanying drawing. The drawing shows the preferred arrangement of elements. The essential characteristics are summarized in the claims.

25 Referring briefly to the drawing, Fig. 1 is a perspective view of the entire device; Fig. 2 is a transverse cross section therethrough in a plane cutting the impression receiving sheets and carbon sheets crosswise; 30 Fig. 3 is a fragmentary detail interior perspective view of the corner construction showing the relation of parts for holding the carbon sheets; Fig. 4 is a similar detail perspective outside view, showing the carbon sheet holding device closed; that is to 35 say, in sheet holding position; Fig. 5 is a perspective view similar to Fig. 4, but showing the carbon sheet holding device in open position.

40 Referring more in detail to the drawing, 1 indicates a suitable base preferably made from a flat slab of material, such as wood. The block of impression receiving materials is indicated at A, and the carbon sheets at 45 B, and B'. The arrangement illustrated is designed to serve as a self-contained support and retainer for a block of printed paper forms, and specifically for original, duplicate and "memorandum" bills of lading.

50 A convenient arrangement of the forms is in "fan-fold," that is to say, the entire block is comprised of a single strip folded first one way and then the other, and perforated along the line of fold to facilitate 55 the removal of one sheet at a time, or as

many as is necessary for a single transaction. The original, which directly receives the impression is indicated at a, the duplicate copy at b, and the "memorandum" or triplicate at c. To obtain such copies, a carbon sheet is placed between the panels a and b, and another carbon sheet between the panels b and c.

It is obviously desirable to have such carbon sheets always available on short notice, and it is just as desirable to maintain the block of bills in place on the base. The carbon sheet holder includes in its construction the holding means for the block. As shown, I provide a pair of sheet metal angle 60 members 2 having base portions 3 resting against the slab 1, and upwardly extending portions 4 running along each side of the block of paper. Both ends of each member 65 2 are bent inwardly toward the block as at 4^a, thus providing corner abutments for retaining the block in place. In order that the angle members may be made from a single piece and to provide the necessary 70 characteristics to hold the block at its four 75 corners, the base portion 3 is slit, as at 3^a, to facilitate bending the portions 4^a at right angles. All portions of the base 3 may be secured to the slab, as by screws 5. In order 80 to reinforce the members 2 and to prevent 85 the upper edge of the portions 4 from cutting the carbon sheets the portion 4 is folded on itself, as at 4^b, thus presenting a smooth upper edge.

In the present embodiment, as above explained, it is desired to hold two carbon sheets, and I therefore provide both members 2 with clamping devices in the nature of bails 6. The bail ends 6^a overlap and are 90 hinged to the members 4^a along respective axes passing through the side portions of the block of paper. The hinges may comprise rivets 9 passing through the portions 4^a and 6^a. The inwardly bent or end portions 6^a of the bails are, as shown, single strips of 95 sheet metal, preferably dropped below the doubled edge of the part 4, and between the end portions the metal of the bail strip is doubled downwardly, as at 6^b, in order to 100 embrace the portions 4 of the members 2 with only sufficient clearance to insure a firm grip on the carbon sheet as shown in Fig. 2. To initially position a carbon sheet, its edge to be attached is simply laid over the upright portion of one of the members 2 105 110

and the bail swung down, doubling the margin of the carbon sheet over the portion 4, as shown. The bail is thereafter held in place by friction. By reason of hinging the bail at its two ends as shown, the entire length of the sheet is clasped at once, hence there is little danger of tearing the sheet in putting it into place as described.

From the above description, it will be seen that I have provided a retaining device for a block of sheets arranged in any manner, whether individual sheets secured at one edge, or in fan-fold arrangement, as shown. It will be further seen that I have provided means in connection with such block retaining means which will clasp a carbon sheet and hold it securely in a convenient position for insertion between adjacent sheets of the block. It will be further seen that the carbon sheet holding arrangement is very cheap to manufacture, being made of pressed sheet metal, and that, by reason of the arrangement of parts, no jagged edges resulting from inaccuracy in cutting the sheet metal will be presented in such position as to injure the carbon when in unfolded position, or tear the clothing of the clerk using the device.

I claim:

1. In a device of the character described, a base to receive and support a block of paper, means engaging adjacent corners of such block to hold the block in place on the base, and means pivotally secured to the first-named means at opposite sides of the block of paper and arranged to cooperate with the first-named means to clamp a sheet of impression transferring material in position to be inserted between the sheets of the block.

2. In a device of the class described comprising a support to hold a block of superposed sheets, means to secure an impression transferring sheet in cooperative relation to the sheets of the block comprising an angle member having one flange thereof secured to said support and the other extending upwardly alongside the block, a bail, and means supporting its two ends, said bail being swingable about an axis passing through the block and parallel to the side

edges thereof, said bail being recessed to cooperate with the upwardly extending flange to grip an edge of such transferring sheet.

55

3. In a device of the character described, a base to receive and support a block of paper, a sheet metal strip supported by the base and extending along one side of the block, said strip having its ends bent to extend past respective corners of the block to position the same, and means pivotally secured to the said ends, said means being recessed to fit over the strip to secure an impression transferring sheet in cooperative relation to the sheets of the block.

60

4. In combination with means to support a block of superposed paper sheets, a pair of twice bent members adapted to embrace the block, and bails associated with each of said members and respectively hinged thereto at both ends, said bails being adapted to cooperate with the bent members to secure carbon sheets at respective sides of the block.

70

5. In a device of the class described, a single piece sheet metal strip having a base flange and a longitudinally folded upright flange presenting a smooth uppermost edge by reason of the fold, the folded ends of the strip being bent transversely flatwise, and a bail comprising a single piece of sheet metal strip doubled longitudinally to provide spaced flanges adapted to fit over the upright flange to hold a transfer sheet, and having transversely bent end portions respectively pivoted to the bent ends of said first-named strip.

75

6. In a device for supporting a block of paper, means adjacent the edges of the block for securing transfer sheets including block positioning members having upright flanges, a pair of members and supporting brackets therefor, said pair of members being hinged at their ends to respective brackets and swingable about parallel axes, said hinged members having spaced apart body portions adapted to fit over the upright flanges to double and grip such sheets.

80

In testimony whereof, I hereunto affix my signature.

WILLIAM T. BAILEY.
